UNITED STATES PATENT OFFICE.

ALICE M. STOVER, OF GUTHRIE CENTRE, IOWA.

DESIGN FOR A TABLE-TOP.

SPECIFICATION forming part of Design No. 31,157, dated July 4, 1899.

Application filed February 18, 1899. Serial No. 706,085. Term of patent 7 years.

To all whom it may concern:

Be it known that I, ALICE M. STOVER, a citizen of the United States, residing at Guthrie Centre, in the county of Guthrie and State of Iowa, have invented a new and original Design for a Table-Top, of which the following is a specification, reference being had to the accompanying drawings, in which—

Figure 1 is a plan view of the table-top, and Fig. 2 a transverse sectional view thereof.

The letter A designates a circular solid wooden top.

B is a continuous metal fender. It is some larger in diameter than the top A and attached

thereto by means of brackets C, that are fixed 15 to the top to project upward, so as to retain the fender in a plane above the top of the wooden surface.

Having described my invention, what I claim as new, and desire to secure by Letters 26 Patent therefor, is—

The design for a table-top as herein shown and described.

ALICE M. STOVER.
